US00D981434S

(12) **United States Design Patent** (10) **Patent No.:** **US D981,434 S**
Hart et al. (45) **Date of Patent:** **** Mar. 21, 2023**

(54) **DISPLAY SCREEN OR PORTION THEREOF WITH GRAPHICAL USER INTERFACE**

(71) Applicant: **Capital One Services, LLC**, McLean, VA (US)

(72) Inventors: **Colin Hart**, Arlington, VA (US); **Lea Cody**, Arlington, VA (US); **Charles Nathan Crank**, Henrico, VA (US); **Daniel Herrington**, New York, NY (US); **Jason Ji**, Reston, VA (US); **Lara Mossler**, Farmville, VA (US); **Jeffrey Rule**, Chevy Chase, MD (US); **Kevin Widener**, Chesterfield, VA (US)

(73) Assignee: **CAPITAL ONE SERVICES, LLC**, McLean, VA (US)

(**) Term: **15 Years**

(21) Appl. No.: **29/678,464**

(22) Filed: **Jan. 29, 2019**

(57) **CLAIM**

The ornamental design for display screen or portion thereof with graphical user interface, as shown and described.

DESCRIPTION

FIG. 1 is a front view of a display screen or portion thereof with graphical user interface showing a first embodiment of the claimed design;

FIG. 2 is a second embodiment thereof; and,

FIG. 3 is a third embodiment thereof.

The large broken line rectangle shows a display screen. All broken lines outside of the display screen show portions of a device. All broken lines within the display screen show portions of the graphical user interface. None of the aforementioned broken lines form part of the claimed design.

1 Claim, 3 Drawing Sheets
